CLAIM

The ornamental design for a perforated carton, as shown and described.

DESCRIPTION

FIG. 1 is a bottom perspective view of a perforated carton showing our new design.

FIG. 2 is a top perspective view thereof.

FIG. 3 is a bottom plan view thereof.

FIG. 4 is a top plan view thereof.

FIG. 5 is a front elevation view thereof.

FIG. 6 is a back elevation view thereof.

FIG. 7 is a left side elevation view thereof; and,

FIG. 8 is a right side elevation view thereof.

The lightweight dashed lines in the figures show unclaimed subject matter and do not form any part of the claimed design. The normal weight dotted lines in the figures represent claimed perforations.
